UNITED STATES PATENT OFFICE.

GABRIEL RODRIGUEZ, OF MATANZAS, CUBA.

CIGARETTE-HOLDER.

SPECIFICATION forming part of Letters Patent No. 252,140, dated January 10, 1882.

Application filed September 9, 1881. (No model.)

To all whom it may concern:

Be it known that I, GABRIEL RODRIGUEZ, of Matanzas, Cuba, have invented a new and useful Improvement in Cigarette-Holders, of which the following is a specification.

My improvements relate to cigarette-holders made collapsible in order that they shall retain their contents in good condition at all times, and also made water-proof to exclude dampness and perspiration.

The object of my invention is to furnish inexpensive holders of substantial character; and it consists in the novel features of construction hereinafter described and claimed.

In the accompanying drawings, Figure 1 is a side view of my improved cigarette-holder formed with the opening at one end. Fig. 2 is a longitudinal section, and Fig. 3 is a cross-section, of the holder. Fig. 4 is a longitudinal section of the same as made from a single piece of material. Fig. 5 is a side view, Fig. 6 is a longitudinal section, and Fig. 7 is a cross-section, of the holder as made with a side opening. Fig. 8 is a cross-section of the same, made in a single piece. Fig. 9 is a plan view of the paper covering used with the holders.

Similar letters of reference indicate corresponding parts.

I make use of card-board, parchment, or other material of suitable stiffness, which is cut in suitable lengths to form the sides *a* of the holder. These pieces may be flat or curved on three edges, as shown in Figs. 2, 3, 6, and 7, one edge being left flat where the opening of the holder is to be. The curvature may vary, and the sides *a*, instead of being in two pieces, may be in a single piece, bent at its center either longitudinally or transversely, as shown in Figs. 4 and 8. The sides *a* are retained together by a band or ring, *b*, of india-rubber, which serves as a spring to compress the holder, and also allow its expansion. This ring may extend transversely or longitudinally,

and be placed at the center or near one end of the holder, and in either position will act to 45 press the case or holder tightly upon its contents.

To cover the separated sides and ends of the holder I use an outer covering, *c*, of paper or other thin material that will readily fold. This 50 is to be cut of the form shown in Fig. 9 when the holder is made in the flat form shown in Figs. 1 and 5, and is to be attached at one edge or side *a* of the case and folded upon the other side. The flap formed at one side of the cover 55 *c* is to cover the open end of the case. This cover protects the contents of the case at the separated sides, and, being flexible, will not interfere with the expansion and contraction. When the sides are made in one piece, as shown 60 in Figs. 4 and 8, the cover is to be applied in the same manner as above described, and the only difference between them being that in Figs. 4 and 8 the sides or ends are only covered with flexible material, while in the other 65 figures the sides or ends and bottoms are covered with flexible material.

The body of the case may be made of card-board, wood, sheet metal, or any suitable material, and the covering may be paper, muslin, 70 or other flexible material. The size of the case will be regulated by the length of the cigarettes and the greatest number to be carried at once. The form may be flat, as shown in Figs. 1 and 5, or of any other suitable form. 75

Having thus described my invention, I claim as new and desire to secure by Letters Patent—

The collapsible cigarette-holder consisting of stiff side portions, *a*, and folded covering *c*, provided with elastic band *b*, substantially as 80 shown and described.

GABRIEL RODRIGUEZ.
